(57) **CLAIM**

The ornamental design for a lamp as shown and described.

DESCRIPTION

1. Lamp

FIG. 1.1 is a top plan view of the lamp showing my new design.

FIG. 1.2 is a front plan view of the lamp.

FIG. 1.3 is a right side plan view of the lamp.

FIG. 1.4 is a top perspective view of the lamp.

FIG. 1.5 is a bottom perspective view of the lamp.

FIG. 1.6 is a bottom plan view of the lamp.

The lamp features an organic bow shape, expanding at its nonagon center and tapering to each end. The lamp can be installed individually, clustered or wall mounted. The left side plan view is identical to the right side plan view, and the back plan view is identical to the front plan view.
